(57) **CLAIM**

The ornamental design for a transport container for animals, as shown and described.

DESCRIPTION

1. Transport container for animals

1.1 is a front perspective view of a transport container for animals showing my new design;

1.2 is an exploded view thereof with the base of the container in a flipped position showing the bottom and back sides of the base;

1.3 is a perspective view thereof in an open position;

1.4 is a top plan view thereof;

1.5 is a front elevational view thereof; and

1.6 is a detailed perspective view of the top portion thereof.
